United States Patent Office

Des. 208,861

Patented Oct. 10, 1967

208,861

COMBINED ELECTRON DISCHARGE DEVICE AND FITTINGS THEREFOR

Benjamin V. Valles, San Jose, Calif., assignor to Litton
Precision Products, Inc., San Carlos, Calif., a corpora-
tion of Delaware

Filed Aug. 18, 1966, Ser. No. 3,516

Term of patent 14 years

(Cl. D26—8)

FIG. 6

FIGURE 1 is a perspective view of the preferred design of a combined electron discharge device and fittings therefor.

FIGURE 2 is a side elevational view of the combined electron discharge device and fittings therefor of FIGURE 1.

FIGURE 3 is a top view of the combined electron discharge device and fittings therefor of FIGURE 1.

FIGURE 4 is a perspective view of a modified embodiment of the device shown in FIG. 1.

FIGURE 5 is a side elevational view of the combined electron discharge device and fittings therefor of FIGURE 4.

FIGURE 6 is a top view of the combined electron discharge device and fittings therefor of FIGURE 4.

I claim:

The ornamental design for a combined electron discharge device and fittings therefor, substantially as shown and described.
